DESIGN FOR A LIGHTING FIXTURE

Thomas W. Rolph, Newark, Ohio, assignor to
Holophane Company, Inc., New York, N. Y., a
corporation of Delaware

Application June 26, 1940, Serial No. 93,253

Term of patent 14 years

To all whom it may concern:

Be it known that I, Thomas W. Rolph, a citizen
of the United States of America, and a resident
of Newark, in the county of Licking and State
of Ohio, have invented a new, original, and or-
namental Design for a Lighting Fixture, of which
the following is a specification, reference being
had to the accompanying drawing, forming a part
thereof.

In the drawing:

Figure 1 is a side elevational view of a lighting
fixture showing my new design; and

Figure 2 is an inverted plan view.

I claim:

The ornamental design for a lighting fixture,
as shown.

THOMAS W. ROLPH.
